J. W. BLACK

DEVICE FOR OPERATING OIL GAUGES

Filed Jan. 19, 1924

Inventor:
Joe W. Black,
By Dyerforth, L. S., Clinton, N. H.
Attys.

UNITED STATES PATENT OFFICE.

JOE W. BLACK, OF CHICAGO, ILLINOIS.

DEVICE FOR OPERATING OIL GAUGES.

Application filed January 19, 1924. Serial No. 687,379.

To all whom it may concern:

Be it known that I, JOE W. BLACK, a citizen of the United States, residing at Chicago, in the county of Cook and State of Illinois, have invented a new and useful Improvement in Devices for Operating Oil Gauges, of which the following is a specification.

This invention relates to devices for operating oil gauges and the like and is particularly adapted to be used on Ford cars where the two oil level gauges are very inaccessible.

The primary object of the invention is to provide a device which will make it easy to open and close these oil gauges, which is positive in its action, and which at the same time while being substantial and satisfactory in its operation, is relatively inexpensive to manufacture and install.

These and other objects as will appear from the following description are fully described in the following specification and shown in the accompanying drawings in which:

Figure 1 is a partial transverse vertical section through an automobile chassis showing my device applied thereto;

Fig. 2 is an enlarged side elevation of the U-shaped operating member; and

Fig. 3 is a top plan view of the same.

This is an improvement on the construction shown and described in my pending application Serial No. 633,214, filed April 19, 1923.

The embodiment illustrated comprises a U-shaped sheet metal operating member 10 having openings 11 in its ends, these openings being adapted to be placed over the flattened ends 12 of the tapered plugs of the petcocks 13 which are commonly placed in the crank case 14 of a Ford substantially as shown in Fig. 1.

The petcocks 13 are turned so that the plugs 12 are in alignment and face in the same direction, the flattened ends of the plugs 12 being uppermost. The openings 11 of the U-shaped member 10 are adapted to be placed over these flattened ends and may then be securely fastened thereon by being squeezed together at 15 as by means of pliers.

A rod 16 has one end bent at 17 and adapted to pass through a hole 18 in the

member 10. A cotter pin 19 passes through the end of this rod and retains it in the hole 18. The opposite end of the rod 16 passes through an opening in the running board shield 20 and has a knob 21 secured on the outer end as by means of a cotter pin 22.

A spring 23 passes over the rod 16, one end of the spring bearing against the inner side of the shield 20 while the opposite end bears against a washer 24 which is secured on the rod 16 by means of a pin 25. This spring is under compression at all times so that the U-shaped member 10 is normally held in the closed position shown.

When it is desired to test the level of the oil in the crank case 14, the operator takes hold of the knob 21 and drawing it outwardly compressing the spring 23 and causes the U-shaped member 10 to turn the plugs 12 thereby opening the petcocks 13. The observer then looks under the running board 26 to see what oil is running from both petcocks 13. From the observed flow he is able to judge of the level of oil in the crank case. Oil will flow as long as the knob 21 is held out, thereby maintaining the petcocks open. As soon however as he releases the knob 21 the spring 23 forces the rod 16 and the U-shaped member 10 back to the position wherein the petcocks are closed.

Because of the inclined positions of the petcocks an outward pull of the rod 16 in addition to turning the plugs 12 also has a tendency to pull them outwardly against the action of their springs 27. As the plugs 12 are tapered, the larger end being upward toward the flattened ends 12, this has a tendency to loosen the plugs and prevent their sticking during the operation of opening them. During the reverse operation of closing the pressure of the rod 16 tends to force these tapered plugs toward their seats, thereby insuring that they are properly closed.

While I have shown and described certain embodiments of my invention, it is to be understood that it is capable of many modifications. Changes therefore in the construction and arrangement may be made without departing from the spirit and scope of the invention as disclosed in the appended claims, in which it is my intention to claim all novelty inherent in my invention as broadly as possible in view of the prior art.

I claim:

A device for operating two crank-case petcocks having aligned plugs pointing in the same direction, said device comprising a member adapted to engage said plugs, means extending to an accessible point for operating said member, and a spring for returning said member to a normally closed posi-

tion, the plugs being inclined toward the operating means, so that said operating means tend to withdraw the tapered plugs as they are turned toward open position and to force said plugs into the petcocks as they are turned toward closed position. ¹⁰
